179,437

EXPANSIBLE CHAIN FOR A BRACELET OR SIMILAR ARTICLE

Karl C. Augenstein, Cranston, R. I., assignor to Speidel
Corporation, Providence, R. I., a corporation of Rhode
Island

Application August 20, 1956, Serial No. 42,661

Term of patent 14 years

(Cl. D45—4)

FIG. 1

FIG. 2

FIG. 3

FIG. 4

Fig. 1 is a fragmentary view of an expansible chain for a bracelet or similar article, showing my new design, with portions thereof shown in broken lines for convenience of illustration;

Fig. 2 is a fragmentary plan view thereof, showing the chain in a partially expanded condition;

Fig. 3 is an enlarged plan view of one of the links shown in Fig. 1; and

Fig. 4 is a side elevational view of one of the links of Fig. 1, with the conventional side wall thereof being shown in broken lines.

I claim:

The ornamental design for an expansible chain for a bracelet or similar article, substantially as shown and described.
